PORATION OF DELAWARE.

JACQUARD FOR CIRCULAR-KNITTING MACHINES.

Application filed September 12, 1924. Serial No. 737,250.

The object of our invention is to provide a very simple and efficient jacquard device for controlling the formation of the stitches or loops in a circular knitting machine, in order that the knitting machine may be caused to produce various designs or patterns composed of plain or groundwork stitches intermixed with special stitches. Heretofore, it has been customary to provide special or cut wheels for controlling the beards of the knitting needles so that by holding certain beards in closed position and others in the open position variations in the formation of the stitches were produced under the control of the special or cut wheel. For the regular groundwork stitch a wheel was used which had teeth for engaging every beard of the many needles. The special or cut wheel produced a special or fancy stitch according to the formation of the periphery of this wheel; and various mechanisms have been used for placing either one of the wheels into operation, such as a cam, but such mechanisms have not been adapted to produce more than a limited variation of pattern. In the present device it is possible to produce by means of a simple jacquard card a great many patterns or designs by means of the automatic control. For instance, the special stitch may be formed at different intervals around the tube of fabric on one line of stitches and at other intervals on succeeding lines of stitches, in order to create effects similar to the grain of wood, moiré effects, various figures, and in fact almost any simple or complex design may be formed according to the perforations in the jacquard card. These results are obtained in the present case by means of very simple devices which may be attached to or applied to knitting machines now in general use so that it is unnecessary to construct a special machine for the employment of the present invention. Other advantages will be set forth in the following detailed description.

In the drawings forming part of this application,

Figure 1 is an elevation of part of a circular knitting machine having the present invention applied thereto,

Figure 2 is a sectional view taken on the line 2-2 of Figure 1,

Figure 3 is a plan view of the solenoid and the wheels for controlling the needles,

Figure 4 is a side elevation of the same parts,

Figure 5 is a sectional view taken on the line 5-5 of Figure 4,

Figure 6 is an enlarged detail view showing the action of the wheels on the beards,

Figure 7 is a sectional view showing the circuit controlling levers and the manner in which they are operated by the jacquard card,

Figure 8 is a sectional view taken on the line 8-8 of Figure 7, and

Figure 9 is a perspective view showing a portion of the pattern controller or jacquard card adapted to be used with the present machine.

Figure 10 is a diagram of the electrical circuits.

It is to be understood that the present invention may be used in conjunction with a single or multiple feed or, in other words, in a machine where a single thread is fed to the circular bank of needles, or where two or more threads are simultaneously fed to the bank of needles. Where the machine is being operated with a single feed there will be one set of devices as described herein-after, whereas for operating with a multiple feed certain parts of the mechanism will be duplicated according to the number of feeds; although the same jacquard card may be used for either the single or multiple feed. In Figure 1 there is shown a portion of a tube of fabric 1 which is being formed or knitted at the circular bank of needles 2 supported upon the usual needle frame or base 3 which latter is adapted to be revolved with the carriage 4 in accordance with the present practice in circular knitting machines. Each needle 2 is provided with the usual beard 5 and as is well known in the art, different stitches may be formed by the control of these beards; and as the construction of a stitch is such as follows standard practice it is unnecessary to describe in detail the present invention to describe in detail the formation of the stitches.

In the several figures of the drawings there is shown an upper wheel 6 which is journaled to turn freely upon a vertical shaft 7

which is carried by arm 8 suitably supported upon a frame 9 which is attached by means of the bracket 10 to the bed of the machine. The arm 8 is adjustably held on the frame 9 by means of the screw 11 so that the arm 8 may be adjusted toward and from the bank of needles sufficiently to secure proper position of the wheel 6 in relation to the beards of the needles. The wheel 6 is of a special or cut type, having slots 12 in its periphery interspaced with small grooves 13 the wheel being adapted to be revolved by contact with the several needles in the bank. When the slot 12 registers with the beard of a needle such beard remains open, whereas when a groove 13 registers with a beard the wheel forces the latter into closed position; and these slots and grooves may be cut in the wheel 6 in various arrangements or patterns, according to the particular type of special stitch which is to be produced upon the fabric. Where the beard remains open it will be understood that the loop is not cast off but is held by the needle until some succeeding operation, whereas, when the beard is held in closed position the loop is cast off. It may here be stated that except for the devices herein described the entire knitting machine, including the feed, cloth wheels and lander wheels and cast-off wheels may all conform to standard practice. This special or cut wheel is so mounted that it is always in operative position in regard to the needles although it will only close certain beards, according to the formation of its periphery, but it is in active position in relation to the bank of needles at all times. There is a slide 14 slidably mounted in the frame 9 and on one end it carries a vertically disposed shaft or stud 15 on which is mounted a beard wheel 16 which turns freely upon this stud and it lies in a horizontal position parallel with and adjacent to the upper wheel 6. This latter wheel 16, is adapted to cause the formation of the plain or groundwork stitch and for this purpose its periphery is of saw-tooth formation with regularly formed serrations or teeth 17 which are adapted to act upon the beard of each successive needle while this wheel is in active position, the wheel being adapted to be revolved by the needles as they pass it. The slide 14 on which this second wheel is carried extends across the frame 9 and it is adapted to be moved in one direction by means of a coiled spring 18 one end of which is connected with a pin 19 on the slide and the other end of which is connected with the hook of an adjusting screw 21^a carried by the bracket 20 which is secured to a bar 21 of the frame. This spring tends to move the slide 14 in the direction which will cause the wheel 16 to move away from the needles. There is a solenoid 22 mounted upon a member of the frame 9 and having a magnetic core member

23 projecting at one end; and this solenoid is adapted to attract an armature 24 which is shown of L shape and attached to the slide 14 by means of the screw 25. There is a screw 26 extending freely through an aperture 27 in the armature and it is adapted to screw into an aperture 28 in the frame, the purpose of the screw being to limit the movement of the slide 14 to the left in Figure 4.

The device for controlling the operation of the electric circuit, which includes the solenoid, is as follows:

In Figs. 1 and 2 there is shown a gear 29 carried by the shaft or central post of the needle carriage and there is a gear 30 mounted on a short shaft 31, having its bearing in the bracket 37, forming part of the casting which is attached to the bed of the machine. Also fixed on the same shaft with the gear 30, so as to turn with gear 30, is a mitre gear 32 which meshes with and drives another mitre gear 33 which is fixed to a shaft 34 also having its bearings in a portion of the casting 37 this latter shaft being disposed at right angles to the shaft 31. On the opposite end of the shaft 34 there is a sprocket 35 over which travels the chain 36 and the latter also travels over the sprocket 38 which is loose on the shaft or bar member 39. This member 39 is non-rotatably fixed in a bracket supported from the table or bed of the machine. The chain above described, is here shown as designed to cause the sprocket 38 to make one revolution for every revolution of the needle bank. On the shaft 39 there is a pair of sprocket wheels 40 which are spaced apart by an intermediate ring 41, the sprockets and rings being clamped together by means of the screws 42 so that the three parts revolve on the shaft 39 as a unit. A set screw 66 fastens them to sprocket 38. The pattern controller which is the jacquard card 43 shown in Figure 9, in addition to a central row of pattern markings, i. e. perforations 44 to be referred to hereinafter, also has near each side edge a row of regularly spaced perforations 45 which register with the teeth 46 of the sprockets 40 so that the jacquard card may be positively fed through the action of the teeth 46 projecting through the feed perforations 45 of the card, and the intermediate portion of the card containing the row of perforations 44 rests against the periphery of the spacing ring 41. This jacquard card may be made of stock such as flexible cardboard or heavy paper such as is commonly used for various jacquard cards.

In addition to traveling around the sprockets 40 the jacquard card also passes around an idler roller or rollers such as 47 attached to some part of the supporting table, it being intended that the card should be joined together to form a continuous strip.

There are shown in the present drawings two circuit controlling devices as the machine is set up for a double thread feed, but it will be understood that there may be 5 only a single circuit controller where there is a single thread feed or there may be three, four or more circuit controlling members where a corresponding number of thread feeds are employed on a machine. These 10 circuit controlling devices are preferably adjustable in position to accord with the positions of the thread feeding devices in relation to the needle bank. In Figures 1, 7 and 8 there is shown a disc 48 mounted on 15 and fixed to the shaft 39 and there is an arm 49 pivoted upon the shaft 39 and projecting horizontally past the sprocket wheels 40. The position of this arm 49 is adjustable by means of the screw 50 in the arcuate slot 51 in the disc 48. The arm 49 also carries a plate 52 having a binding post 53 to which one end of the wire 54 connects, the other end connecting with the lever arm 55. The plate 52 has also a post 56 in 20 which is mounted a contact screw 57 which is adjustable in the post and which is adapted to be fixed in position by the set screw 58. The lever 55 pivoted to the arm 49 by the screw 60 and one arm 61 of this lever, 25 which is very short, comprises a pawl having a narrow edge which is adapted to be acted upon by the jacquard card where the latter lies against the face of the ring 41. The other arm 55 of this lever is considerably longer than the pawl and is adapted 30 to make the contact with the contact screw 57. There is a coiled spring 62 having one end attached to the lever arm 55 and the other end is attached to a bracket 63 carried by the arm 49, and this spring tends to 35 draw the arm 55 into contact with the contact screw 57 and to maintain the pawl 61 in contact with the jacquard card or with the ring 41. The second circuit controlling 40 device is shown in the drawing as positioned ninety degrees from the one just described and its construction and operation are the same with the exception that this vertical arm 49 is arranged on a pivot pin 64 in a 45 slot in the disc 48 so that it may be swung into a position to bring the pawl 61 into engagement with the jacquard card or it may be swung entirely away from the card to take it out of operation. This may be desirable 50 where the machine is changeable from a double to a single feed or vice versa. As the construction of both controlling devices is otherwise the same the same reference numerals have been applied to both of 55 these devices. It will be understood that the wires 65 connected with the coil of the solenoid and wires connecting with the binding post 53 and with the post 57 are connected in series with any source of current 60 such as the electric light circuit of the build-

ing, although the source of current may be a battery if desired. The electrical circuits are shown in Fig. 10.

Operation.

70

The jacquard card will have a row of perforations 44 extending along the middle of the card as shown in Figure 9 and these perforations will be of different lengths and 75 will be spaced different distances apart, according to the pattern which is to be produced in the fabric. The pattern to be worked out in the jacquard card will be perforated on any suitable perforating machine which is no part of the present invention. The jacquard card will be threaded on the teeth of the sprockets 40 and around the idler 47 and the two ends will be connected in any suitable manner so that the 80 card forms an endless belt. In the drawing the card is exaggerated in thickness for the purpose of illustration. When the machine is in operation the needle bank and frame will be revolved counter-clockwise, in 85 Figure 3, in the usual manner, and motion will be imparted through the chain of gears shown in Figure 2 and through the chain 36 to the sprocket 38 and this will revolve the sprockets 40 which are pinned by the 90 pin 66 to the hub of the sprocket 38 these members revolving freely on the shaft 39. As the jacquard card is drawn around the periphery of the ring 41 by the sprockets 40, it acts upon the pawls 61 of the contact 95 levers, and if the thread feeds are positioned ninety degrees apart around the bank of needles these contact levers will be spaced ninety degrees apart, so that the card will 100 act upon the pawls 61 at different points corresponding with the positions of the thread feeds on the machine. As each contact arm 55 is connected with a separate solenoid and controlling device (see Fig. 10), each contact arm will separately control a stitch forming device so that each of these performs the same operation but at different positions around the bank of needles. Considering one of these circuit 105 controlling devices and the associated mechanisms, the operation will be as follows, it being understood that the other devices are duplicates and operate the same. As a solid portion of the card passes under the pawl 110 61 the lever 55 is rocked against the resistance of the spring 62 until the free end of this lever disengages from the contact point 57 and this breaks the circuit which includes the source of current and the coil of the respective corresponding solenoid. While this 115 condition exists the slide 14 is held in the left hand position in Figure 4 so that the wheel 16 is disengaged from the beards of the needles. When a perforation in the 120 jacquard card registers with the pawl 61 the 125 130

contact lever is permitted to swing under the action of the spring 62 until the free end of the lever arm 55 contacts with the screw 57 and at such time the circuit, including the source of current and the coil of the solenoid, exerts a magnetic pull on the armature 24 drawing the same to the right in Figure 4, and this moves the slide 14 to the right in opposition to the spring 18 until the periphery of the wheel 16 aligns with the periphery of the fixed wheel 6. Thus the circuit will be alternately opened and closed by the contact arm 55 and the periods during which the circuit is opened and closed will vary according to the arrangement and length of the various perforations 44 in the jacquard card, and these periods will all be timed in relation to the revolution of the needle bank and therefore with the formation of the stitches by the knitting mechanism.

At all times the wheel 6 is in position to act upon the beards of the several needles, and when the wheel 16 is in the retracted position shown in Figure 4 the special stitch will be formed by the wheel 6 according to the shape of its periphery. This action will result whenever the solid or imperforate part of the jacquard card holds the pawl 61 over in position to keep the contact arm 55 away from the contact screw 57. When a perforation in the jacquard card comes into registry with the pawl 61 the latter passes through the perforation and the outer end of the contact lever 55 strikes the contact screw 57 and this closes the electric circuit and energizes the coil of the solenoid. The magnetic pull of the solenoid 22 attracts the armature 24 and this forces the slide 14 to the right in Figure 4 until the wheel 16 is pressed against the beards of the adjacent needles and until the wheel 16 vertically aligns with the wheel 6. Both wheels will now be revolved by the needles, that is to say, while the solenoid is energized. As the lower wheel 16 engages the beard of every passing needle while it is in the active position, the action of the upper wheel 6 will simply be nullified and the ordinary ground or plain stitch will be formed in the fabric instead of the special stitch which was previously formed under the control of the upper wheel. This action will continue until a solid portion of the jacquard card lifts the pawl 61 and disengages the contact arm 55 from the contact screw 57. When this occurs the circuit will be opened, de-energizing the solenoid, and the spring 18 will move the slide 14 to the left in Figure 4 and retract the wheel 16 from the needles. This, however, leaves the upper wheel 6 to engage with the needles so that this wheel again functions to cause the production of the special stitch. These operations may be repeated at short or long intervals, accord-

ing to the pattern produced. As the pattern may be varied both circumferentially and lengthwise of the fabric any form of design may be produced. It will be noted that the needles are always under the control of either the wheel 6 or the wheel 16 and it is preferable that the upper wheel remain constantly in the operative position. Both of the circuit controlling devices shown in the drawings operate in the manner just described and additional controlling devices may be provided for controlling any additional sets of beard wheels.

Having described our invention, what we claim is:

1. The combination of a knitting machine having a bank of needles, a plurality of beard wheels adapted to operate at the same point on the beards of said needles, and means for moving one of said beard wheels into and out of operative position, including a solenoid adapted to move one of said beard wheels into operative relation with the beards of said needles, a spring for retracting said beard wheel out of operative position, a jacquard card, and means controlled thereby for energizing said solenoid.

2. The combination of a knitting machine having a bank of needles, a plurality of groups of beard wheels, each group comprising a plurality of wheels adapted to operate at the same point on the beards of the needles and said groups of beard wheels acting at different positions on the bank of needles, a jacquard card and means for operating it, and a plurality of devices simultaneously operable at different points on the said jacquard card, and means controlled by said latter devices for separately causing one of the beard wheels of each group to be moved into and out of operative relation with the bank of needles.

3. The combination of a knitting machine having a bank of needles, a plurality of beard wheels adapted to operate at the same point on the beards of said needles, one of said wheels being stationary, a movable slide on which the other of said beard wheels is mounted to move into and out of vertical alignment with the stationary beard wheel, a solenoid, an armature mounted on said slide and adapted to be moved by said solenoid to place the movable beard wheel into operative position, a spring for retracting said slide, a jacquard card and means controlled thereby for energizing said solenoid.

4. The combination of a knitting machine having a bank of needles, a plurality of beard wheels adapted to operate at the same point on the beards of said needles, and means for moving one of said beard wheels into and out of operative relation, including a solenoid, a jacquard card, a lever having one arm actuated by said jacquard card, another arm of said lever being adapted to

make and break an electric circuit including said solenoid.

5. The combination of a knitting machine having a bank of needles, a plurality of beard wheels acting at the same point on the beards of said needles, and means for moving one of said beard wheels into and out of operative position, including a revolvable support and a jacquard card travelling

10 around said support, a lever having one arm engaging and controlled by said jacquard card, another arm of said lever being adapted to open and close an electric circuit, and electric means actuated thereby for moving

15 one of said beard wheels.

6. The combination of a knitting machine having a bank of needles, a plurality of beard wheels acting at the same point on the beards of said needles, and means for moving one of said beard wheels into and out of operative position, including a revolvable support and a jacquard card traveling around said support, a lever having one arm adapted to be actuated by said jacquard

25 card, another arm of said lever being adapted to control an electric circuit, means for adjusting the position of said lever around said revolving card support, and electrical

means controlled by said lever for moving

30 one of said beard wheels.

7. The combination in a knitting machine, of a circular bank of needles, a plurality

of spaced groups of knitting-controlling wheels, electrically actuated means for controlling the position of a wheel of each group, a jacquard card, and a circuit opening and closing device, responsive to said card, for each of said means, one of said circuit opening and closing devices being adjustable to and from another of said circuit opening and closing devices.

8. The combination of a bank of needles, a plurality of spaced feeds therefor, each feed including a plurality of knitting-controlling wheels, a pattern controller means for operating said controller, and a plurality of means responding to the same pattern markings of said pattern controller for causing a wheel of each feed to move into and out of operative relation with the bank of needles, each of said means causing the movement of a wheel of one of said feeds and said means being spaced apart so as to be acted on successively by the pattern controller, the spacing between said means relative to the pattern controller being equivalent to the spacing between the feeds relative to bank of needles.

Signed at the city, county and State of New York, this 10th day of September, 1924.
